UNITED STATES PATENT OFFICE.

WESTERN UNDERWOOD, OF LOS ANGELES, CALIFORNIA, ASSIGNOR OF ONE-HALF TO
H. H. WALKER, OF LOS ANGELES, CALIFORNIA.

GLOBE-MOUNTING RING.

Application filed December 26, 1923. Serial No. 682,600.

This invention has to do with a ring useful in mounting glass globes, or the like, in holders.

Glass globes and like devices, for instance, 5 globes of street lighting units, etc., are usually retained in suitable holders by means of set screws, or the like, the set screws being carried by the holders and engaging lips formed on the globes. Considerable breakage occurs 10 in globes of this character, due largely to the mountings. The set screws, if set too tight, break the globes or hold them under pressure so that they break if they become heated and expand or if pressure, for instance, wind 15 pressure, comes upon them. While, if the set screws are set too loose the globes are not properly held and are subject to becoming released from the holders and to breakage due to movement in the holders. Further, the 20 holders are usually unfinished castings, and, therefore, do not present uniform or smooth supports for the globes.

It is a general object of this invention to 25 provide a device useful in mounting a globe so that the globe is not subject to breakage as above outlined.

It is an object of the invention to provide 30 a device whereby a globe can be securely and effectively mounted in a usual holder without danger of being injured or broken, and which 35 does not require any change or modification of the globe or holder.

Another object of this invention is to provide 35 a device for mounting a globe in a holder so that the globe can expand or contract without binding or becoming loose.

Another object of this invention is to provide 40 a device for mounting a globe in a holder so that it is uniformly supported and gripped.

Another object of this invention is to provide 45 a device for use in mounting a globe in a usual holder so that the set screws of the holder can be made tight without danger of breaking or binding the globe.

Another object of this invention is to provide 50 a device of the character above mentioned which is simple and convenient to use and which does not interfere in any way with the appearance of the globe or holder.

The various objects and features of my 55 invention will be best and more fully understood from the following detailed description of a typical preferred form and application of the invention, throughout which descrip-

tion reference is had to the accompanying 55 drawing, in which:

Fig. 1 is a top plan view of the device provided by this invention; and

Fig. 2 is a fragmentary sectional view of a portion of the holder and globe, showing 60 the device of the present invention employed in mounting the globe in the holder.

In the drawings I have illustrated a simple and typical globe holder 10, comprising a flat annular seat 11, a vertical flange 12, extending 65 upwardly from the outer edge of the seat 11, and set screws 13 carried by the flange to engage and hold a globe 14, or the like, that may be arranged in the holder. The globe 14, illustrated in the drawings, is provided with 70 the usual annular lip 15, adapted to be arranged in the holder 10. The lip 15 is designed and constructed to be engaged and held by the set screws 13. The outer side of the particular lip illustrated in the drawings 75 is concave to receive the end portions of the set screws.

The present invention provides a ring 18 to be employed at the mounting or point of connection between the holder and globe. 80 The ring 18 is a split or ended metal ring including, generally, a lip engaging part 19 and a holder engaging part 20. The holder engaging part 20 is adapted to be supported and held in the holder 10, and is preferably 85 a liplike part adapted to be arranged in the holder to be supported by the seat 11 and engaged by the set screws 13. It may be shaped, for instance, made concave, so that it receives the set screws and is, therefore, effectively 90 held by them. The lower edge of the holder engaging part may be straight so that it will seat upon the seat 11 of the holder.

The lip engaging part 19 is intended to engage and hold the lip 15 of the globe. In 95 order that the part 15 may be effective in gripping and holding the lip it is preferred that it be shaped and proportioned to more or less accurately and closely fit the lip, as I have illustrated in Fig. 2 of the drawings. 100 For instance, when the lip of the globe is concave, as I have shown in the drawings, it is desirable that the lip engaging part be correspondingly shaped. In accordance with the preferred form of the invention a seat 21 105 is provided at the lower edge of the lip engaging portion to engage under and support the globe. The seat may be in the form of a

flange extending inwardly from the lower edge of the lip engaging part 20. The seat 21 is, of course, smooth and regular so that it evenly and uniformly supports the globe.

5 In accordance with my invention the holder engaging part and lip engaging part of the ring are connected or joined together in spaced relation. The parts 19 and 20 are preferably arranged concentrically and one 10 within the other, as I have shown in the drawings. In the present case the lip engaging part is smaller in diameter than the holder engaging part and is therefore arranged in the holder engaging part. With this arrangement and relationing of the parts 19 and 20 it is convenient to join or connect their upper edges together by a suitably curved part 22. The parts 19 and 20 are free to expand or contract more or less independently of each other, 15 so that they independently fit or engage the parts with which they are adapted to cooperate. The parts 19 and 20 are spaced a substantial distance apart so that they can be flexed or distorted considerably before interfering with one another. Further, the parts 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500

In practice I prefer to form the device of sheet metal, preferably from a single piece of sheet metal. The device can be advantageously formed from a single piece of sheet metal by spinning. I employ a metal that is more or less resilient so that the device may be sprung around the lip of a globe and will operate in the manner I am about to describe. When I use the term "resilient" I mean a degree of resilience sufficient for successful operation of the device as described. The ring should have enough resilience so that it can be sprung onto a globe without being bent past its elastic limit and so that it can likewise be tightly applied to the globe.

In using the ring provided by this invention it is applied at the point of connection between the globe and holder. The ring is arranged around the lip of the holder so that the part 19 engages the lip and the lower end of the lip engages the seat. The holder engaging part 20 of the ring is arranged in the holder so that its lower edge rests upon the seat 11. The set screws 13 are then tightened.

against the part 20 causing the entire ring to contract and thereby grip the lip of the globe. The set screws may be tightened firmly against the part 20 without danger of injuring the globe or putting it under excess pressure. The construction of the device allows the parts 19 and 20 to properly seat and adjust themselves to the holder and globe and allows for sufficient movement between the parts 19 and 20 so that the part 20 can be sprung somewhat inwardly by the screws. As a matter of fact the pressure of the set screws applied at a few points around the device causes a general and substantially uniform contraction of the device and is distributed so that it is applied substantially uniformly around the lip of the globe. With the pressure of the set screws thus evenly distributed around the lip of the globe it is possible to set the screws particularly tight without danger of injuring the globe or putting it under uneven strain. Further, the part 19 and seat 20, in conforming closely to the shape of the lip, support the globe uniformly and effectively reinforce and protect the lip.

Having described only a typical preferred form of my invention I do not wish to limit myself to the specific details hereinabove set forth but wish to reserve to myself any changes or variations that may appear to those skilled in the art or fall within the scope of the following claims.

Having described my invention, I claim:

1. An insert for supporting a globe in a holder including a single body of metal shaped to form a resilient split ring substantially U-shaped in cross sectional configuration, one side of the ring having a flange at its outer edge extending in a direction transverse of the axis of the ring.

2. A single body of metal shaped to form a resilient split ring for use in connection with a globe and holder therefor, the ring including two spaced flange like parts, one within the other, and having their upper edges connected together, one adapted to be held by the holder and the other adapted to hold the globe, the globe holding part having an inwardly extending flange to support the globe.

In witness that I claim the foregoing I have hereunto subscribed my name this 13th day of December, 1923,

WESTERN UNDERWOOD,

110
